Grover Atterbury Inventor

UNITED STATES PATENT OFFICE.

GROSVENOR ATTERTBURY, OF NEW YORK, N. Y.

MOLD.

1,241,487.

Specification of Letters Patent.

Patented Oct. 2, 1917.

Application filed April 19, 1916. Serial No. 92,192.

To all whom it may concern:

Be it known that I, GROSVENOR ATTERTBURY, a citizen of the United States, residing in the city, county, and State of New York, have invented certain new and useful Improvements in Molds, of which the following is a description.

My invention relates particularly to molds or forms for use in casting blocks of concrete or other cementitious material.

One object of my invention is to provide a mold of this character whereby blocks of the desired form may be cast with the least possible expense of time and labor.

Another object of my invention is to provide such a mold which shall be inexpensive in construction and reliable and efficient in operation.

A more specific object of my invention is to provide a mold which after the block has been cast therein can be readily adjusted to permit of the ready separation of the block and mold.

With the above and other objects in view, as will more fully hereinafter appear, my invention comprises broadly the provision of a mold having a pair of side pieces of any desired form, and one or more pairs of end pieces interposed therebetween. I provide means, preferably manually operable, for adjusting the side pieces toward and from each other, so that they may be retracted from the block which is being cast, when desired. The two end pieces of each pair are also adjustable toward and from each other for the same purpose, and I preferably so construct the means for effecting this latter adjustment that they will be brought into operation to retract the end pieces after the side pieces have been retracted a predetermined distance. The object of thus delaying the retraction of the end pieces is to cause them to retain the block or blocks in position until the side pieces have been separated therefrom, and thus prevent the block or blocks from adhering to one or the other of the side pieces and cores.

Referring to the drawings:

Figure 1 is a plan view of my improved device;

Fig. 2 is a transverse sectional view thereof, taken on the line 2-2 of Fig. 1, and showing the parts in position to receive the moldable material; and

Fig. 3 is an end elevation thereof showing the parts in such position as to permit the removal of the completed block or blocks therefrom.

My improved mold includes a pair of 60 parallel side pieces 10 Fig. 2 which, as herein illustrated, are constructed of plates 11 and angle bars 12, the plates 11 being bent over at the top, and bottom, to form blocks having rounded edges. The particular construction of the side pieces will, of course, depend upon the form of block it is desired to cast.

These side pieces are adjustable toward and from each other, and any suitable or 70 desired means may be employed for effecting this adjustment. As herein shown, however, I employ a screw 13 having oppositely threaded portions 14, 15, which are in threaded engagement with apertures in the 75 blocks 16, 17, respectively, secured to the side pieces in any desired manner. The screw 13 is preferably provided with some such means as the handle 18 whereby it may be rotated manually.

It is apparent that when the screw 13 is thus rotated, the side pieces will be adjusted toward or from each other, depending upon the direction of rotation of the screw 13.

In order to maintain the side pieces 10, 85 at all times in parallelism, I preferably employ some such means as the hinges 19, the ends of which are pivoted to the side pieces as shown in Figs. 2 and 3, and which are of sufficient width to constrain the movement 90 of the side pieces.

Interposed between the two side pieces 10 are the end pieces 20 arranged in pairs. Any desired number of pairs of end pieces may be employed, depending upon the number of blocks it is desired to cast at one time. I have herein shown a mold provided with two pairs of end pieces 20 whereby two blocks may be simultaneously cast in the apparatus, and when such a construction is employed I preferably locate the adjuster 13 between the two central end pieces as shown in Fig. 1. The end pieces herein illustrated are constructed in substantially the same manner as the side pieces, that is, of angle 95 bars and plates, the latter being bent over at the top and bottom, but it is obvious that the form and manner of construction of the end pieces may be changed as desired. Each of the end pieces 20 is provided with 110

a pair of rods or members 21. The central portion 22 of each of the members 21 is of greater length than the end piece to which it is secured, and the end portions 23 of these members are bent at an angle to the end pieces. The members 21 pass through apertures 24 Fig. 2 in the side pieces 10. The object of this particular construction of the rods or members 21 will appear more fully hereinafter.

The side pieces 10, preferably have secured thereto one or more cores 25, which when the apparatus is in position to receive the material to be molded as shown in Fig. 1, contact at their inner ends, and thus form one or more voids through the blocks which are cast.

As herein shown, these cores are tapered and are all of the same size and shape, but it is obvious that any desired form of core and any desired number thereof may be employed.

The manner in which my apparatus operates is as follows:

Assuming the various parts to be in the positions shown in Fig. 1, the apparatus is placed upon a suitable plate or pallet, such as is indicated at 26 in Figs. 2 and 3, and the cementitious or other moldable material is poured therein in semifluid condition. The material is then permitted to harden, and when it has acquired a sufficient degree of hardness, the handle 18 is rotated, thereby retracting the side pieces 10 from the block or blocks being cast. Obviously since the cores 25 are secured to the side pieces 10, they will also be retracted as a result of the rotation of the handle 18.

Since, as above described, the central straight portions 22 of the members 21 are somewhat longer than the end pieces 20, to which they are attached, the initial retractile movement of the side pieces 10 will have no effect upon the end pieces, but these end pieces will be held against the block or blocks being cast. The result of this is that the blocks are held firmly in position by the end pieces, while the side pieces are separated therefrom, so that there is no danger of the block or blocks adhering to one or the other of the side pieces or cores and being moved thereby. After the slight initial movement of the side pieces, however, the apertures 24 thereof cooperate with the angular ends 23 of the members 21, with the result that the end pieces are cammed away from the block or blocks. By continuing to rotate handle 18, the side pieces 10 may be separated to such an extent that the cores 25 are completely withdrawn from the block or blocks being cast. The blocks and the mold may then be separated either by removing the blocks from the mold or by removing the mold from the plate 26.

The hinges 19 maintain the side pieces in

parallelism during their retraction, as above indicated, and the end pieces are retained in parallelism during their retraction by the pairs of members 21 which pass through the apertures 24 of the side pieces.

I am aware that it has heretofore been proposed to provide for the simultaneous retraction of four hinged walls of a mold by means of members somewhat similar to the members 21 of my improved mold. But so far as I know, I am the first to so construct these members so as to delay the retraction of the end pieces until after the initial retraction of the side pieces, or to employ such members in connection with rectilinearly movable end pieces (as distinguished from hinged end pieces), in which connection they serve the additional function of maintaining the end pieces in parallelism.

The end pieces 20 are preferably provided with roughened surfaces or indentations (not shown) for the purpose of forming better bonding surfaces in the completed blocks. Such a construction also facilitates the holding of the blocks in position by the end pieces during the initial retractile movement of the side pieces.

While I have herein described but a single embodiment of my invention, it is obvious that many changes may be made herein without departing from the spirit of my invention.

What I claim is:

1. A mold for casting a block of cementitious material, comprising a pair of substantially parallel side pieces, a pair of end pieces interposed therebetween, means operable at will for simultaneously retracting the side pieces from the block, and means operated by the retractile movement of the side pieces for retracting the end pieces from the block, said last mentioned means being so constructed that they become operative to retract the end pieces after the side pieces have been retracted for a predetermined distance.

2. A mold for casting a block of cementitious material, comprising a pair of substantially parallel side pieces, provided with apertures, a pair of substantially parallel end pieces interposed therebetween, means operable at will for simultaneously retracting the side pieces from the block, and a pair of angularly bent members secured to each of said end pieces adjacent opposite ends thereof and passing through the apertures in said side pieces whereby the retractile movement of the side pieces will cause the retraction of the end pieces from the block, and the end pieces will be maintained in parallelism during their retraction.

3. A mold for casting a block of cementitious material, comprising a pair of substantially parallel side pieces provided with

apertures, a pair of end pieces interposed therebetween, means operable at will for simultaneously retracting the side pieces from the block, and rods secured to the end 5 pieces and passing through the apertures in the side pieces, each of said rods comprising an intermediate portion of greater length than the end piece to which it is secured and parallel thereto, and end portions disposed angularly to said end pieces whereby the end pieces will remain stationary during the initial retractile movement of the side pieces and will thereafter be retracted thereby.

15 4. A mold for casting a block of cementitious material, comprising a pair of substantially parallel side pieces, a pair of end pieces interposed therebetween, means operable at will for simultaneously retracting 20 the side pieces from the block, a plurality of hinges having their ends pivoted to said side pieces for maintaining the side pieces in parallelism during their retraction and means operated by the retractile movement 25 of the side pieces for retracting the end pieces from the block.

5. A mold for casting a block of cementitious material, comprising a pair of substantially parallel side pieces, a pair of substantially parallel end pieces interposed therebetween, an actuator provided with oppositely threaded portions in threaded engagement respectively with said side pieces for retracting said side pieces from the 30 block, and means operated by the retractile movement of the side pieces and adapted to come into operation subsequently to the retraction of the side pieces from the block for retracting the end pieces from the block 35 and for maintaining them in parallelism during such retraction.

40 6. A mold for casting a block of cementitious material, comprising a pair of substantially parallel side pieces, a pair of substantially parallel end pieces interposed therebetween, a core secured to one of said side pieces, means operable at will for simultaneously retracting the side pieces and core from the block, and means operated by the retractile movement of the side 45 pieces for retracting the end pieces from the block and for maintaining them in parallelism during such retraction.

7. A mold for casting a block of cementitious material, comprising a pair of substantially parallel side pieces, a pair of end pieces interposed therebetween, a tapered core secured to each of said side pieces, the inner ends of said cores being normally in contact whereby a void is formed through 55 the block, means operable at will for simultaneously retracting the side pieces and the cores from the block, and means operated by the retractile movement of the said side pieces for retracting the end pieces from the 60 block.

8. A mold for simultaneously casting a plurality of blocks of cementitious material comprising a pair of substantially parallel side pieces, a plurality of pairs of 65 end pieces interposed therebetween, one of the end pieces of one pair being adjacent one of the end pieces of another pair, an actuator interposed between said adjacent end pieces and provided with oppositely 70 threaded portions in threaded engagement respectively with said side pieces for retracting said side pieces from the block, and means operated by the retractile movement 75 of said side pieces for retracting the end 80 pieces from the block.

9. A mold for simultaneously casting a plurality of blocks of cementitious material comprising a pair of substantially parallel side pieces, a plurality of pairs of end 85 pieces interposed therebetween, one of the end pieces of one pair being adjacent one of the end pieces of another pair, an actuator interposed between said adjacent end pieces and provided with oppositely 90 threaded portions in threaded engagement respectively with said side pieces for retracting said side pieces from the block, and means operated by the retractile movement 95 of said side pieces for retracting the end pieces from the block, and for maintaining said end pieces at all times in parallelism, said last mentioned means being so constructed that they become operative to retract the end pieces after the side pieces 100 have been retracted for a predetermined distance.
